UNITED STATES PATENT OFFICE.

JOHN M. HUDSON, OF NEW YORK, N. Y.

IMPROVED CONSTRUCTION AND RIGGING OF TRESTLE-TREES FOR VESSELS.

Specification forming part of Letters Patent No. **56,754**, dated July 31, 1866.

To all whom it may concern:

Be it known that I, JOHN M. HUDSON, of the city, county, and State of New York, have invented a new and improved mode of constructing and rigging the trestle-trees of vessels and of adapting the connecting-rigging with the lower mast-heads, the heel of the top-masts, and the working of the top-sails; and I do hereby declare that the following is a full and exact description thereof, reference being had to the accompanying drawings, and to the letters of reference marked thereon.

The nature of my invention consists in putting a trestle-tree, B, on the lower mast, X, below the upper trestle-tree, A, Figures 1, 2, 4, and to extend the heel of the top-mast C, putting a band, G, around the top-mast Y, to truss the lower yard, T, in, and placing a bridle-band, E, around and over the mast-head for slinging the lower yard, T, to.

D is a projection on the ends of the lower trestle-trees, B. F is an iron gate on the upper trestle-tree, A. H are hounds bolted on the mast X to support trestle-trees A and B. I is a wooden top resting on upper trestle-tree, A. J represents the lowest place of top-sail yard V in old style, Fig. 3. K is the point where lower mast-head is cut off. L are clew-lines leading to ends of yard V and down side of sail to the clews M or lower corners of top-sail. N are spilling-lines which go around the sail. O is the chain-slings of lower yard, T. P is a wood fid through heel C of top-mast Y, to support the weight resting on lower trestles, B, and taking against the projections D on the ends of the same. Q is a front view of the bridle-band E. R is the chain or rope gear top-sail sheets, which hook into the top-

sail clews M. S is the top-sail halyard for hoisting yard V. U is an iron band around trestle-trees B. Z is a parral-iron to connect top-sail yard V to top-mast Y for hoisting and lowering, the top-sail coming all the way down the top-mast to iron gate F on upper trestle-trees, A, easing the weight and making it more safe in heavy weather.

The sail can be easily reefed or furled by hauling on the clew-lines L, which bring the sail tight across the reef-bands. By hauling on the spilling-lines N the sail is bound up to the top-sail yard V and made secure.

W is top-mast cross-trees for supporting top-mast rigging, Fig. 1.

What I claim as my invention, and desire to secure by Letters Patent, is—

1. The placing below the upper trestle-trees, A, a new pair of trestle-trees, B, on the lower mast, X, with the projections D on the ends, and securing trestle-trees B with the iron band U, and extending the top-mast Y so that the heel C with fid P, going through the heel C, will rest on trestle-tree B and take against the projections D, instead of resting on the trestle-trees A, which now opens with the iron gate F to facilitate sending the top-mast Y up and down, substantially in manner as herein described.

2. The bridle-band E over the mast-head, as herein described.

3. The combination of the foregoing with the clew-lines and spilling-lines, for the purposes and objects herein described.

J. M. HUDSON.
